US00D782910S

(12) **United States Design Patent** (10) Patent No.: **US D782,910 S**
(45) Date of Patent: **** Apr. 4, 2017**

(54) **BOTTLE**

(71) Applicant: **PepsiCo, Inc**, Purchase, NY (US)

(72) Inventors: **Jorge Manuel Maquita Nakano**,
Distrito Federal (MX); **Lori Evans**
Bartman, Sylvania, OH (US)

(73) Assignee: **PepsiCo, Inc.**, Purchase, NY (US)

(**) Term: **15 Years**

(21) Appl. No.: **29/537,876**

(22) Filed: **Aug. 28, 2015**

(51) LOC (10) Cl. **09-01**

(52) U.S. Cl.

USPC **D9/538**

(57) **CLAIM**

The ornamental design for a bottle, as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

(Continued)

The broken lines in the figures show portions of the bottle that form no part of the claimed design. The dot-dash broken lines are boundary lines that form no part of the claimed design.

1 Claim, 7 Drawing Sheets
